REED MOUNTING FOR SIFTERS

Peyton M. Thompson, Lockport, N. Y., assignor
to International Milling Company, Buffalo,
N. Y.

Application October 12, 1936, Serial No. 105,176

15 Claims. (Cl. 209—415)

This invention relates to improvements in sifters and more particularly to means for yieldingly supporting the sieve or screen housing of a sifter.

One of the objects of this invention is to provide a mounting of improved construction by means of which the rods or reeds supporting the sifter housing may be flexibly attached to a base or other part to permit the same to swing about the point of attachment and also to move to a limited extent in the direction of their length. Another object of this invention is to provide a spring mounting for a reed of a sifter in which the spring is so arranged that it may flex to act as a universal joint between the reed and the base. A further object is to provide a mounting in which a spring is arranged to act as a universal joint between the base and the reed and also to permit a limited movement of the reed in the direction of its length.

Other objects of the invention will appear from the following description and claims.

In the accompanying drawings:

Fig. 1 is a perspective view of a sifter having a mounting embodying this invention applied thereto.

Fig. 2 is a plan view, on an enlarged scale, of the reed mounting, showing the same secured to the base of the sifter.

Fig. 3 is a side elevation thereof, partly in section.

Fig. 4 is an end elevation thereof, partly in section.

Fig. 5 is a section thereof on line 5—5, Fig. 2. The word "sifter" as herein used is intended to apply to any apparatus for sifting, screening or bolting materials for the purpose of separating the same according to their particle sizes and the sifter shown in the accompanying drawings is illustrated merely by way of example, since it will be obvious that the sifter supporting devices embodying this invention may be used in connection with sifters of other constructions.

In Fig. 1, A represents the body or sieve housing of the sifter to which the materials to be sifted may be fed in any suitable manner, and from which the sifted materials may be separately discharged. The sieve housing A is mounted in such a manner as to cause the material which is being sifted to be quickly passed over and through the screens or sieves and for this purpose, the sieve housing is flexibly mounted so as to permit the desired movement of the housing. In the particular construction illustrated, the sieve housing A is supported from a base B,

by means of upright rods or reeds C, one end of each of which may be suitably clamped to the sieve housing A, as for example at 8, and the other ends of which are flexibly connected with the base B, which in the construction shown has four outwardly extending legs to the ends of which the reeds C may be flexibly secured. The sifter also includes means for imparting movement to the sieve housing, such for example, as a motor D mounted on the base B and connected by means of a belt E to a crank wheel F which is journalled on the base B and which has a crank pin journalled in a self-aligning bearing in the lower part of the sifter housing A. This connection imparts to the lower part of the housing A a substantially circular motion and the upper corners or parts of the housing A to which the upper ends of the reeds C are connected also have a modified circular motion, which is accompanied by a slight up and down movement. This motion of the sieve housing results in a very efficient and rapid sifting action and also necessitates a circular motion together with a slight amount of vertical movement of those portions of the reeds C which are connected with the housing. The sifter itself is not a part of this invention and forms the subject matter of an application for patent filed by Thomas G. Cecka on June 25, 1936, Serial No. 87,198. This present invention concerns itself mainly with the flexible mounting for the reeds of the sifter to permit the swinging of the reeds about the mounting and also to permit the desired slight amount of longitudinal movement of the reeds.

My improved mounting is shown in the drawings as applied to the outer ends of the legs of the base B, which legs preferably each have a substantially flat base portion 9 reinforced by means of an upright web or rib 10 which terminates at a distance from the end of the leg.

In order to provide a flexible and yielding mounting for the reeds C with relation to a fixed base, I preferably provide one or more flexible strips or springs secured to the base and to the reeds C. In the construction illustrated, two flat leaf springs 12 are shown, one end of each of which is rigidly secured to the base B in any suitable manner, for example, by means of bolts 13 and near the other ends of these springs, reeds C are secured in any suitable manner. For example, in the particular construction shown, clamps are provided for securing the reeds to the springs, including a clamping member 14 rigidly secured in any suitable manner, such, for example, as screws 15 and 16 to the springs 12.

These clamps have upright parts provided with upright grooves or recesses 17 adapted to receive the ends of the reeds C and cooperating clamp members 18 are provided with similar recesses 19. 5 When the two parts 14 and 18 of the clamp are secured together, for example, by means of a bolt 20, the lower ends of the reeds will be securely attached to the outer ends of the springs 12. It will be noted that by means of the construction shown, the springs 12 may be flexed in 10 different directions to form pivotal connections or mountings for lower ends of the reeds, to enable these ends of the reeds to move relatively to the base in such a manner as to enable the upper ends of the reeds to travel in approximately circular paths. The springs, therefore, 15 act as universal joints connecting the reeds and the base. The springs can also flex in such a manner as to permit up and down movement of the reeds C, in the direction of their lengths. 20 It has been found that in the sifting of flour and other finely divided materials, a high efficiency of the sifter can be obtained, if the vertical movement of the reeds C is restricted so as to prevent excessive up and down movement of the 25 reeds within the housing A. Such up and down movement may, of course, be limited by the stiffness of the springs 12, but such stiffness would restrict the ease with which the springs become 30 flexed to permit the same to act more or less as pivots for the lower ends of the reeds C. Consequently, it has been found desirable to make the springs 12 relatively light and flexible and to provide other means for restricting the up and 35 down movement of the reeds C. In the particular construction illustrated, I have accordingly provided at the outer ends of the springs 12 a clamp or stop 25 suitably secured to the base B, for example, by means of screws or bolts 26, and 40 having a toe or projection 27 extending over the outer ends of the springs 12. It is also very desirable to provide suitable resilient means for cushioning the up and down movement of these ends of the springs 12, and any resilient means 45 may be employed for this purpose. In the construction illustrated, I provide a rubber pad 28 between the outer ends of the springs 12 and the base B and another pad 29 between the upper faces of the ends of the springs 12 and the extension or toe 27 of the stop member 25. The 50 pads 27 and 28 may be of any suitable rubber composition having the desired resiliency, and furthermore, the distance between the lower face of the toe or projection 27 and the base B may 55 be such that when the stop member 25 is secured on the base, the rubber pads 28 and 29 will be under compression. Since the lower pad 28 must support a part of the weight of the sieve housing, it is preferably somewhat larger in size 60 than the upper pad 27.

The parts of the stop device described can be readily designed or proportioned so as to provide for the desired up and down movement of the ends of the springs 12. For the sifting and 65 bolting of flour, for example, it has been found that a movement of approximately $\frac{1}{16}$ of an inch in an up and down direction of the reeds C produces the maximum sifting efficiency and if it should be found that for other materials, a different vertical movement is desired, this can be 70 readily obtained by replacing the pads 28 and 27 with pads of greater or less resiliency or by providing stop devices in which the toes or extensions 27 are spaced at greater distances from the base B. My improved mounting can, therefore,

be readily adapted to suit various conditions which may be encountered. The mounting is also such that it is very durable and not subject to deterioration. Furthermore, all of the parts of the mounting are readily removable and accessible so that repairs or replacements can quickly be made. It will further be noted that the yielding mounting for the ends of the springs provided by the stop device further assists the springs in their flexing to provide for a pivotal movement of the adjacent ends of the 10 reeds. 15

While the mounting is herein described as forming a connection between the lower ends of the reeds C and the base B, it will be obvious that my improved mounting may, if desired, be used for connecting the upper ends of the reeds to the sifter housing A or for mounting the reeds C from an overhead support. While the device illustrated in the drawings shows two reeds used 20 at each corner of the sifter, it will be obvious that the device may equally well be used with a single reed or with more than two reeds. It will also be understood that the word "base" as herein used is intended to include not only a specially 25 constructed sifter base such as shown in the drawings, but any part to which a reed may be secured, such for example as a floor, a ceiling, or overhead support or a part of the sieve housing itself, since it will be obvious that the mounting 30 described may be employed at either or both ends of the reeds. It will also be understood that the drawings illustrate merely one embodiment of this invention and that it is not intended to limit the invention to the particular embodiment 35 illustrated.

I claim as my invention:

1. In a sifter having a sieve housing and a base, reeds supporting said housing from said base, a flexible connection between a reed and said base, 40 including a leaf spring having its flat face arranged substantially horizontally and having a portion thereof secured to a base and having the reed secured to another portion thereof to permit flexing of said spring in accordance with the 45 movement of said reed.

2. In a sifter having a sieve housing and a base, reeds supporting said housing from said base, a flexible connection between a substantially upright reed and said base including a leaf spring 50 secured near one end thereof to said base and having a reed secured to the spring at a distance from said end, the flat face of said spring being arranged substantially in a horizontal plane, to permit a limited universal movement 55 of the part of said spring to which said reed is connected, and a movement thereof in the direction of the length of the reed.

3. In a sifter having a sieve housing, a base, reeds supporting said housing from said base, a 60 connection between a reed and said base, comprising a substantially horizontally extending flexible strip having a part secured to a base and a movable part positioned at a distance from the first mentioned part, and means for securing a 65 reed to said movable part.

4. In a sifter having a movable sieve housing supported from a base by reeds, and connections between said substantially upright reeds and said base, each comprising a substantially horizontally extending metal leaf spring having a portion thereof secured to said base and having a reed connected to another portion of said spring which is free to flex relatively to said base to 75

form a universal joint connection between said base and said reed.

5. In a sifter having a movable sieve housing supported from a base by reeds extending upwardly from said base and connected with said housing at their upper ends, and connections between said reeds and said base, each comprising a leaf spring extending substantially at a right angle to said base and having a portion thereof secured to said base and having a reed connected to another portion of said spring which is free to flex to form a universal joint connection between said base and said reed, said spring also being flexible in a direction to permit movement of the reed in the direction of the length of the reed.

6. In a sifter having a sieve housing and a base, reeds supporting said housing from said base, a flexible connection between a reed and said base, including a leaf spring extending substantially at a right angle to said reed having one part thereof secured to the base and another part which is flexible relatively to said first mentioned part and to which said reed is secured, and means for limiting the movement of said reed in the direction of its length.

7. In a sifter having a sieve housing and a base, reeds supporting said housing from said base, a flexible connection between a reed and said base, including a leaf spring having a portion thereof secured to a base and having the reed secured to another portion thereof to permit flexing of said spring in accordance with the movement of said reed, and stop means engaging said spring to limit movement of the same in the direction of the length of said reed.

8. A connection between a base and a reed supporting a sieve housing, comprising a flexible strip having a face thereof lying in a substantially horizontal position having a part secured to said base and a movable part positioned at a distance from the first mentioned part, means for securing a reed to said movable part, and means engaging said movable part to limit the movement of the same in the direction of the length of said reed.

9. A connection between a base and a reed supporting a sieve housing, comprising a substantially horizontally extending flexible strip having a part secured to said base and a movable part positioned at a distance from the first mentioned part, means for securing a reed to said movable part, and resilient stop means engaging said movable part to limit movement thereof in the direction of the length of said reed.

10. A connection between a base and a reed supporting a sieve including a leaf spring extending substantially at a right angle to said reed and having a part thereof secured to said base,

and a clamp secured to another part of said spring and to which said reed is secured.

11. A connection between a base and a reed supporting a sieve including a pair of leaf springs, each having one end thereof connected to said base, and a bracket connecting the other ends of said springs and to which said reed is secured, to permit said reed to swing to different angular relations to said base and to move in the direction of its length.

12. A connection between a base and a reed supporting a sieve including a flexible strip having a part thereof secured to said base and having a reed secured to another part thereof, and resilient pads arranged at opposite faces of said strip to limit the movement thereof by said reed, said flexible strip permitting said reed to move in the direction of its length and said pads limiting said lengthwise movement of said reed.

13. A flexible mounting for an upright reed on a base, including a pair of leaf springs arranged in substantially parallel relation to each other and having their flat faces lying in substantially horizontal planes and having one end of each spring secured to said base, a clamp engaging an end of a reed and secured to the opposite ends of said leaf springs, and stop means engaging the ends of said leaf springs adjacent to said clamps and having resilient pads confined at the upper and lower faces of said springs for limiting the vertical movement of said springs.

14. In a sifter including two parts, one of which is movable relatively to the other part, reeds having their opposite ends connected to said parts for forming a flexible connection between said parts to permit movement of one part relatively to the other, a leaf spring extending substantially at a right angle to a reed and connected at a portion thereof to one of said parts and having an end of the reed connected to another portion thereof, to permit flexing of said spring in accordance with the movement of said reed.

15. In a sifter including two parts, one of which is movable relatively to the other part, reeds having their opposite ends connected to said parts for forming a flexible connection between said parts to permit movement of one part relatively to the other, a leaf spring extending substantially at a right angle to a reed and connected at a portion thereof to one of said parts and having an end of the reed connected to another portion thereof, to permit flexing of said spring in accordance with the movement of said reed, and resilient stop means arranged to limit the movement of said spring relatively to the part to which said spring is connected.

PEYTON M. THOMPSON.
